GRINDING MILL

Axel Larsen, Aalborg, Denmark, assignor to F. L. Smith & Co., New York, N. Y., a corporation of New Jersey

Application August 19, 1932, Serial No. 629,444
In Great Britain November 23, 1931

4 Claims.

(CL. 83—9)

This invention has been developed with particular reference to the grinding of cement raw material, either in the dry state or in the wet state, but, as will be obvious, it is capable of adaptation to the grinding of other materials with full realization of its advantages. The improved mill overcomes disadvantages incident to the use of ball mills and tube mills, such as have been used commonly heretofore in grinding cement raw materials, in that, in the operation of the improved mill, it is possible to inspect the grinding operation at all times and to make from time to time such adjustments as may be necessary to establish the best working conditions. Furthermore, the power consumption is not great as compared with that of ball mills and tube mills, even with heavy charges, and the weight of the mill can be made considerably less than that of a ball mill or tube mill of the same capacity. As compared with impact pulverizers or hammer mills, in which the material is pulverized by the impact of hammers carried by a rotating member the improved mill, by reason of the fact that it can be operated at a much slower speed, is much less subject to wear and tear and to damage occasioned by especially hard particles. Furthermore, in the operation of the improved mill the grinding of the material is effected by the action of the grinding bodies, whether flint pebbles or metal balls or other bodies, which, with the material to be ground, make up the charge of the mill, the main function of the rotors or stirrers being to effect such relative movement of the grinding bodies as will accomplish the grinding of the material.

The improved mill, in its simplest form, comprises a stationary container or shell which may be open at the top and into which the material to be ground is fed at one end and from which the ground material is delivered at the other end, and a disc-like rotor or series of disc-like rotors which are rotated about the axis of the mill and cause relative rubbing movement without impact of the grinding bodies with which the mill is charged so that they act by attrition rather than by impact. Provision is made for the passage of the material operated upon from the feeding end of the mill to the discharge end while the grinding bodies are retained. It will be understood that the details of construction of the mill can be varied in many ways to suit the conditions of operation and while several different embodiments of the invention are shown and described herein it will be understood that different features of construction can be sub-

stituted for one another or can be used by themselves or in combination with other features, as the conditions of operation may indicate, and that, except as pointed out in the accompanying claims, the invention is not restricted to any particular embodiment.

In the drawings, in which several different embodiments of the invention are illustrated—

Figure 1 is a view, partly in longitudinal section and partly in elevation, of a mill which embodies the invention.

Figure 2 is a view of the same as seen from above.

Figure 3 is a view in transverse section, on the plane indicated by the broken line 3—3 of Figures 1 and 2, showing particularly the preferred construction of each of the rotor discs.

Figure 4 is a transverse section on the plane indicated by the broken line 4—4 of Figures 1 and 2 illustrating particularly the preferred construction of each of the partitions intermediate the rotor discs.

Figure 5 is a view similar to Figure 1 but showing the rotor discs of progressively increasing diameter and the shell as conformed thereto.

Figure 6 is a view in elevation of a rotor in the form of a cage, the intermediate partitions being necessarily omitted.

Figures 7 and 8 are detail views, respectively in section and in elevation, illustrating a device for the control of the movement of the material being ground.

Figure 9 is a view similar to Figure 1, but showing the rotors arranged in groups with a perforated partition between adjacent groups.

Figure 10 is a detail view, in elevation, of a plate which may be introduced in front of each rotor for the purpose of reducing the resistance in starting when the mill is fully charged.

Figure 11 is a detail view showing a rotor yielding connected with the supporting shaft, also for the purpose of reducing the resistance in starting.

In the embodiment of the invention shown in Figures 1—4 the stationary non-rotating shell 45 or casing or container 1, which may be made of steel plates and conform generally, in its lower portion, to the rotor discs to be referred to, and having an open top, is shown as mounted on a suitable base 46 and as receiving axially a shaft 50 on which are mounted, so as to rotate therewith, discs 3, provided with suitable perforations 4. The shaft 2 may be rotated by any suitable means, as, for example, through a gear 5, a pinion 6, and a band pulley 8 keyed on the shaft 7.

of the pinion. Suitable bearings may be provided at 9 for the shaft 2 and at 10 for the driving shaft 1. All of these parts may be supported in any suitable manner as on the base or foundation 11. Suitable packing boxes, as at 12, may be provided in the ends of the shell 1 for the shaft 2.

In this embodiment of the invention there is provided for each disc 3 and in the same plane therewith a diaphragm or partition 13 which fits about the periphery of the disc with a slight clearance, these diaphragms 13 being otherwise imperforate and closing the space between each disc and the casing so that the grinding bodies are held back and all of the material being ground is compelled to pass through the perforations of the disc on its way to the discharge end of the casing. Intermediate the discs 3 with their diaphragms 13 are partitions 14, which may partially encircle the shaft 2 and the hubs 20 of the discs 3 and are formed with perforations, as at 14a.

The stationary non-rotating shell may be provided, as at 15, with a feed hopper and near the other end with a screen 16 which permits the finely ground material to pass through it while retaining the grinding bodies and insufficiently ground material, such finely ground material being delivered through a spout 17 into a suitable transport device not shown. For the purpose of controlling the discharge of the finely ground material the screen, as shown in Figures 7 and 30 8, may be formed of two perforated plates 16a and 16b, one of which may be shifted with respect to the other so as to vary the area of the opening 16c through which the material is permitted to pass.

In the operation of the mill shown in Figures 1-4, it being assumed that the mill has been charged with grinding bodies, as indicated at 18 in Figure 1, and that the rotors have been set in motion, the material to be ground is fed continuously into the mill, entering the chamber formed between the end of the shell and the first rotor. The grinding bodies and the material in each compartment between successive rotor discs are held back by the imperforate partitions 13, the grinding bodies being also retained by the intermediate partitions 14. By the action of the rotor discs the grinding bodies adjacent the discs will have a relative rubbing motion imparted to them and act upon the material by attrition rather than by impact while the grinding bodies adjacent the stationary partitions 14 will have less relative movement. It will be understood, however, that the grinding bodies may be constantly changing their positions between each rotor disc and the adjacent stationary partition. By reason of the relative rubbing movement of the grinding bodies thus established the material to be ground, which fills the interstitial spaces between the grinding bodies, will be ground between the faces of adjacent grinding bodies and also between the faces of the grinding bodies and the faces of the adjacent partitions and rotor discs and such ground material will pass through the perforations 4 of the rotor discs 3 and also through the perforations 14a of the partitions 14, being progressively reduced in fineness until the finely ground material can pass through the screen 16 and so be discharged from the mill. The normal rate of rotation of the shaft 2 and the rotor disc 3 will be comparatively slow and as the progress of the grinding can be observed from the top of the mill, it is a simple

matter to vary the rate of rotation to produce the desired result.

It will be understood that the partitions 13, closely encircling the discs 3, serve to prevent jamming of the grinding bodies between the edges of the discs 3 and the wall of the mill and serve also to compel the material to pass through the apertures of the discs 3 and so obtain a greater grinding effect than would be possible if the material passed outside the disc 3 along the 10 wall of the mill.

While the shell or wall of the container may be conveniently made of steel plates it will be understood that it might be made of concrete, for example, for the wear on the wall of the mill 15 is slight, as it is protected by grinding bodies which have little or no motion. The rotor discs 3 and the partitions 14 should be made of a highly wear resistant material in order to withstand the action of the grinding bodies and for 20 the same reason the rotor discs 3 should be provided with long hubs to cover completely the shaft 2.

It will be understood that if the operation of the mill be started when fully charged the resistance offered by the perforated rotor discs to the moment of starting will be considerable because of the pressure of the grinding bodies and material against the discs. This difficulty may be overcome by provision of slotted plates 19, 30 shown in Figure 10, one of which may be slipped in place in front of each rotor disc when the mill is empty or nearly empty to protect each disc from the pressure of the grinding bodies and material and so reduce the resistance of the mill 35 to the starting moment. When the starting resistance has been overcome the plates can be withdrawn.

As another means of reducing resistance to the starting moment each rotor disc 3a, as shown in Figure 11, can be connected to the shaft 2 through the medium of a spiral spring 3b so that the rotation of the shaft may be started readily and movement imparted gradually to each of the discs.

In the embodiment of the invention shown in Figure 1 the discs 3 are of the same diameter and the lower part of the shell of the mill is cylindrical to conform therewith. If it should be desired either to promote or retard the passage of the material through the mill the discs 3c might be made of successively different diameters, as shown in Figure 5, the shell 1c being conformed thereto and the partitions 13c and 14c being shaped accordingly. In other respects 55 the construction of the mill illustrated in Figure 5 may be the same as that illustrated in Figure 1.

It is obvious that with the partitions 14 omitted the several rotor discs 3d might be united 60 by bars 3e and stay bolts 3f to form a cage-like structure as illustrated in Figure 6, mounted on the shaft 2 to be rotated therewith. Except for the function performed by the perforated partitions 14 of Figure 1 the operation of a mill 65 equipped with such a cage-like structure is the same as that already described with respect to Figure 1, the material as it is ground passing through the openings of the discs 3d while the grinding action is accomplished by the relative 70 movement of the grinding bodies between the discs 3d.

In the embodiment of the invention shown in Figure 9 the rotor discs 3 and the partitions 13 are shown as arranged in groups, with a per- 75

forated partition 14 between successive groups. The operation of such a mill will be readily understood without further explanation.

I claim as my invention:

- 5 1. In a grinding mill, the combination of a stationary, non-rotating shell adapted to receive a charge of grinding bodies and material to be ground and to discharge the ground material, a perforated rotor disc to effect relative movement 10 of the grinding bodies, means to rotate the rotor, and a partition encircling the rotor in the plane thereof and closing the space between the rotor and the fixed shell.
- 15 2. In a grinding mill, the combination of a stationary, non-rotating shell adapted to receive a charge of grinding bodies and material to be ground and to discharge the ground material, a plurality of rotors to effect relative movement 20 of the grinding bodies, perforated partitions interposed between the rotors, fixed imperforate partitions encircling the rotors in the plane thereof and closing the space between the same and the shell, and means to rotate the rotors.
- 25 3. In a grinding mill, the combination of a stationary, non-rotating shell mounted on a

horizontal axis adapted to receive a charge of grinding bodies and material to be ground and to discharge the ground material, a perforated rotor disc mounted on a horizontal axis to effect relative rubbing movement of the grinding bodies without impact, means to rotate the rotor, and a screen at the discharge end of the shell to permit the discharge of the finely ground material and to retain the grinding bodies and coarsely ground material.

4. In a grinding mill, the combination of a stationary, non-rotating shell with a horizontal axis adapted to receive a charge of grinding bodies and material to be ground and to discharge the ground material, a perforated rotor disc 15 mounted on a horizontal axis to effect relative rubbing movement of the grinding bodies without impact, means to rotate the rotor, a screen at the discharge end of the shell to permit the discharge of the finely ground material and to 20 retain the grinding bodies and coarsely ground material, and means to regulate the discharge of the material through said screen.
